OIL PRESSURE AND SPRING CONTROLLED
BUFFER FOR THE SILENT CLOSING OF
DOORSHeinrich Wilhelm Hofius, Dahmeshoved, near
Dahme, GermanyApplication May 17, 1935, Serial No. 22,011
In Germany May 12, 1934

1 Claim. (Cl. 16—85)

This invention relates to an oil pressure and spring controlled buffer for the silent closing of doors.

Hydraulic brakes and buffer rams subjected to spring action are already known. These constructions are so-called shock absorbers for doors which cooperate with cylinders mounted on the door wings. Such cylinders are unsightly and, owing to the complicated construction, they are uneconomical. The pressure in these devices acts in different strengths, also on the shock absorbers, so that by exerting considerable force it is possible to quickly close the door.

The invention overcomes these objections and has for its object to reliably prevent the slamming and banging of doors by very simple means. It must therefore be impossible on the one hand to bang a door by exerting considerable force and it must be possible on the other hand to close the door by exerting slight pressure. This problem is solved according to the invention which utilizes the inertia of the masses which offers considerable resistance under heavy pressure and easily yields under light slowly-applied pressure.

The device according to the invention is characterized in that a buffer ram carrying on its outer end a rubber pad is acted upon by a spiral spring and guided in a cylinder having a conically tapered end with an air outlet aperture and accommodated in an oil container having an air port.

This device enables a perfectly silent closing of the door.

An embodiment of the invention is illustrated by way of example in the accompanying drawing, in which:—

Fig. 1 is a perspective view of the edge of a door frame with a buffer mounted therein.

Fig. 2 is a longitudinal section through the buffer on a larger scale.

A buffer ram *b* with rubber pad *c* is mounted in a lock-like casing in a door frame *a*. Buffers of this kind are preferably arranged between the door lock and the upper and lower ends of the

door respectively. The buffer ram *b* is tightly guided in an oil cylinder *d* and continually pressed outwardly by a spiral spring *e* bearing against its inner end. This spiral spring is likewise mounted in the oil cylinder *d*, the inner end *f* of which conically tapers to a point with an aperture *g*.

As soon as the rubber pad *c* is subjected to pressure by the slamming of the door, its ram *b* forces the oil out of the cylinder *d* through the adjustable aperture *g* into an oil collecting container *h* provided with an air port *v* for the escapement of air.

The door movement is retarded by the new buffer so that no noise is produced by the slamming or gentle closing of the door.

I claim:—

An oil pressure and spring controlled buffer for the silent closing of doors, comprising in combination a casing let into the door frame, an oil container at the inner end of said casing having an air escapement port near its upper end, an oil cylinder in said casing extending from the front wall thereof to the lower end of said oil container, a conical extension on the inner end of said cylinder projecting into said oil container and having at its point a small aperture establishing permanent communication between said container and said cylinder for the free passage of oil between said cylinder and said container, a solid ram slidable in said cylinder and normally projecting from the outer end thereof, said ram adapted to force the oil out of said cylinder through said aperture into said container when pressure is exerted on its projecting outer end, a spiral spring in said cylinder and said conical extension bearing against the inner end of said ram and adapted to return said ram into its initial position and allow the oil to flow from said container through the aperture in said extension to form an oil cushion in said cylinder, and a rubber pad on the projecting outer end of said ram adapted to absorb shocks exerted on said piston.

HEINRICH WILHELM HOFIUS.
